METHOD OF AND DEVICE FOR DEEP SEA
DREDGING

John C. Williams, Oakland, Calif.

Application March 28, 1934, Serial No. 717,808

24 Claims. (Cl. 37—56)

This invention is a deep-sea dredge for dredging at great depths under high hydrostatic pressure where present types of dredges and excavators cannot successfully be used.

In deep sea dredging, it is impractical to use any type of rigid or torsion resistant raising and lowering means for the dredge, the only practical solution of this problem being in the provision of a self-contained unit which is complete in all details as to both, mechanical and driving equipment, and which unit is raised and lowered by flexible means such as a cable or chain through the medium of a winch or hoist mounted on a ship or float above the surface of the water, the dredge being electrically controlled from the surface, merely requiring the operation of a switch for starting and stopping the dredge operating motors.

In all cases where deep-sea dredging has been tried, the chief difficulty encountered has been in the sealing of the enclosure for the motors, especially about protruding shafts, against the high hydrostatic pressures, since with the usual methods of packing, all lubricant is forced out of the bearings by the high pressure existing at great depths, the water following the lubricant and finally filling the enclosure, ruining the motors and causing other damage.

This difficulty has been completely overcome in my invention by means of my new method of packing, in which the pressures are equalized by the exertion of an opposing pressure through the medium of the hydrostatic pressure existent, which same pressure is urging ingress of the water into the enclosure, thus counteracting the pressure urging ingress by the same pressure applied to the lubricant at a point remote from the point of attempted ingress.

Another feature which has caused previous experiments in deep-sea dredging to fail is the fact that no practical solution of the problem of preventing rotation of the sludge receiver when the dredge is operated has been discovered. This problem has been overcome in my invention through the agency of a spud which operates in advance of the cutter head and anchors the receiver against rotation on its own axis.

Values of various descriptions are found in the sea bottom, an example of which is the "gold dust" beds in Alaska, where a high grade sludge forms the bottom of the sea over an extensive area and contains gold dust running in value from nine to forty-five dollars per cubic yard. This material is of very fine mesh of which only grab samples have so far been obtainable.

There are immense deposits of this material which is particularly amenable to flotation and amalgamation, and occurs at depths as great as 160 fathoms, and which is ready for milling operations directly in the form in which it is recovered. 5

The main object of this invention is to provide a dredge which can be operated successfully at the maximum water depths of the aforementioned deposit, which in places approximated one thousand feet below the surface; to recover this material 10 and subject it to flotation, amalgamation or other suitable recovery processes.

Another object of the invention is to provide a dredge with necessary driving motors enclosed in a housing which is effectively sealed against the 15 high water pressures existing at such depths and all other depths, to insure the uninterrupted operation of the dredge.

A further object of the invention is to provide a dredge as an integral unit, surface controlled, 20 self-operating, and which is raised and lowered by means of a flexible line through the medium of a winch or hoist, and which dredge will be self-anchoring against rotation on its own axis when 25 the dredge is operated.

A still further object of the invention is to utilize the pressure of the water for effecting the sealing of all crevices in the motor housing, to prevent leakage or ingress of water especially about protruding shafts, urged by the high water pressure 30 existing about the housing, and to insure the uniform and uninterrupted lubrication of the shafts projecting through the housing walls.

Other objects and advantages of the invention will become apparent as the following description 35 is read on the drawings forming a part of this specification, and in which similar reference characters are used to indicate similar parts throughout the several views, of which;

Fig. 1 is a sectional elevation through the invention with a portion of the receiver broken out. 40

Fig. 2 is a section taken on line 2—2 of Fig. 1.

Fig. 3 is a detail sectional view of the pressure 45 equalized sealing means, shown on an enlarged scale.

Fig. 4 is an enlarged fragmentary sectional elevation showing the cutter head mounting means.

Fig. 5 is an enlarged fragmentary sectional elevation through the driving side of the cutter 50 head.

Fig. 6 is a modification of the system of packing.

Fig. 7 is a modification of the system of packing shown in Fig. 3. 55

Fig. 8 is a sectional elevation through the entrapment valve.

Fig. 9 is a modification of the sealing means.

The invention consists of a deep-sea dredge incorporating a sludge receiver, sludge admitting and retaining means, sludge dumping means, driving means for the sludge dumping means, a cutter head, driving means for the cutter head, a spud or anchor, driving means for the spud, a motor housing or enclosure for the driving motors, means for sealing crevices, or the shafts passing through the walls of the enclosure against ingress of water under varying pressures, valve means normally open, and closed by hydrodynamic pressure during raising of the dredge, and flexible means for raising and lowering the dredge to the bottom of the sea.

The sludge receiver 10 is preferably made cylindrical in form and of any desired length dependent on the nature and depth of material being excavated, a length of ten feet being satisfactory under ordinary conditions.

This receiver may be formed of a length of steel pipe or tubing and a head 11 bolted or welded to the top end of the tube, and suitable water escape holes 12 provided to permit the escape of entrapped water from the receiver as the sludge is admitted at the lower end. A foot 13 is suitably fixed to the lower end of the tube and forms one cooperating face of the dump joint.

The sludge admitting and retaining means is diametrically coextensive with the receiver and is associated with the dumping means and consists of a valve system including bearing faces 14 on which the free edges of the flap valves 15 rest, one of which is shown raised away from the rest 14 for admitting sludge as the receiver settles into the body of sludge. These flap valves are closed by the weight of the sludge when the dredge 40 is lifted, and form a perfect seal to retain the sludge within the receiver when the dredge is raised to the surface.

These flap valves are secured between the annular flange 16 and the ball bearing shroud 17 by means of the bolts 18, the flange 16 being formed integral with the dump body 19. With this valve system it will be noted that as the receiver settles into a bed of sludge, the sludge is admitted into the receiver, the superposed water escaping 50 through the holes 12, or opening 92 controlled by valve 93.

The sludge dumping means consists of the dump body 19, which has an inside diameter equal to that of the tube 10, and has the inwardly projecting annular flange 16 integral therewith. An outwardly projecting annular flange 20 has its top face forming the cooperating face of the dump joint 21. Another outwardly projecting annular flange 22 terminates in an upstanding flange 23 to which the gear shroud 24 is bolted or otherwise affixed, the flange 22 coincidentally forming on its lower surface a shroud for the gear 25, which encompasses the dump body below the flanges 22-23.

65 The hinge for the dumping means consists of a hinge eye 26 which is fixedly secured to the tube 10, and hinge straps 27 which are fixedly secured to the shroud 24 or body 19, as may be found desirable, the pintle of the hinge being shown as a bolt 28. It is important that the pintle be located above the plane of the dump face 21 so as to cause recession of the gear from the pinion as the dump body is dropped, and to insure clearance of other associated parts, such as the 70 shrouds.

The cutter head has a sweep diametrically coextensive with the bottom of the receiver and consists of a cutter holder 29 to which the cutters 30 are secured by known means, this cutter holder being integral with the gear 25 and gear shroud 31, whereby, when the gear is rotated, the cutters are operated, agitating and lifting the material, which is admitted through the valve system to the interior of the receiver.

The cutters are replaceable, and are formed to 10 the shape most suitably applicable to the particular material to be excavated.

The driving means for the cutter head consists of the gear 25, which is supported by the ball bearings 32, which cooperate between the substantially semi-circular raceways formed respectively in the outer face of the dump body below the flange 22, and the inner face of the gear rim, the balls being inserted through a suitable opening, which opening is afterward plugged with a 20 grooved plug registering with the raceway as indicated at 33, the plug being in position when the raceway is machined. The balls obviously support the gear and cutter head on the dump body and coincidentally form a substantially frictionless bearing for the gear.

The gear 25 meshes with a pinion 34 which is fixed on the vertical shaft 35, which in turn is rotatable in the bearings 36 and 37 which are fixedly mounted on the tube 10, and the pinion is 30 provided with suitable shrouds 38 and 39, which are in no way connected to the dump body or cutter head, but are supported by the bearing 36. However, these shrouds have edges formed complementary to the contour of member 31 and to a 35 cut-out portion of the flange 22.

The shaft 35 extends into the sealed motor enclosure 40 through a special pressure-equalizing-packed bearing 41 and has a bevel gear 42 affixed at its upper end. This bevel gear meshes with a 40 mating bevel pinion 43 which is fixed on the shaft of the motor 44. Thus, when the motor is operated, the shaft 35, through pinion 34 drives gear 25 and its integral blade holder 29 with its blades, cutting downwardly into the bed, the sludge being 45 admitted by the valve system into the receiver.

As the boring process continues, the dredge settles down into the bore formed, since the material excavated will not support the dredge by the superficial surfaces exteriorly of the cutters, 50 and where the sludge is sufficiently soft or miry, it is unnecessary to operate the cutter head, since the receiver will sink into the bed while the sludge passes through the valve system into the receiver.

The spud consists of a bar or drill 45, eccentrically located and which projects and operates in advance of the cutter head and is rotatably mounted in a bearing spaced from the bearing 36, and preferably formed in the same casting, and 60 is thus mounted on the receiver proper, and due to its location and operation in advance of the cutter head, it maintains the dredge against rotation on its own axis when the cutter head is operated, and thereby forms an anchor against 65 rotation of the receiver while permitting the receiver and cutter head to settle into the bore as the bore is formed.

The driving means for the spud consists of a pair of mating spur gears 46 and 47 respectively fixed on the spud shaft 48 and drive shaft 35, whereby the spud is driven in unison with the cutter head, although at a higher speed.

The driving means for the dumping means consists of an electric motor 49 having a shaft 75

50 on which is fixed a worm 51, which drives a worm gear 52, which in turn is fixed on a shaft 53 which is rotatably mounted in an equalized-pressure sealed bearing 54, through which the 5 shaft passes to the exterior of the enclosure 40, the outer end of the shaft having a rope sheave 55 secured thereon and a cable 56 windable thereon, and which cable passes through an opening 57, the terminal end of the cable being 10 secured to the dumping means through a lug 58, which is fixed in the wall diametrically opposite the hinge 28.

The means for sealing crevices or shafts passing through the walls of the housing or motor containing enclosure is of especially vital importance, since the failure of all such projects, in 15 connection with deep-sea dredging is attributable to the failure of all methods of packing heretofore used. My method of packing has been 20 under continuous test, submerged in water under eight hundred pounds pressure for many months with no evidence of seepage discernable. This pressure is equivalent to a depth of eighteen hundred and forty feet or three hundred and 25 seven fathoms.

This system of sealing is equally applicable to diving suits, diving bells and other sub-sea devices, and its success is dependent upon the reactive pressure of the water of submergence 30 against ingress of the same water through a lubricating medium of higher viscosity than the water, the packing being increased in resistance and effectiveness as the degree of submergence and the viscosity of the lubricant is increased.

35 The simplest form of this system is clearly illustrated in Fig. 3, in which a bearing 41 is submerged in the water 60, and is provided with the usual bushing 61, and a special bushing 62, in which the shaft 63 is rotatably mounted. The 40 bushing 62 is chamfered to cooperate with the chamfered collar 64, and the pressure of the water at the end 65 of shaft 63 forces the collar 64 against the chamfered seat of the bushing 62, since no pressure exists at the other end of the 45 shaft, which is within the enclosure 40. This feature is not in itself a perfect seal, but merely an auxiliary expedient toward assuring the desired reactive pressure against the other associated elements and to form a seal for the grease, 50 and to increase the pathway and its tortuosity for water of ingress.

An annular chamber 66 is formed in the bearing and encompasses the shaft 63 and is preferably located closer to the end 59 of the bearing 55 than it is to the end 67, and a cylinder 68 filled with a lubricating medium communicates with this chamber, and thence with the bearings.

A piston 69 is urged by a spring 70 under normal lubricating pressure, and the hydrostatic pressure of the surrounding water is transmitted through suitable openings 71 to the top of the piston. A fluid passage 72 communicates between the chamber 66 and a groove 73 formed 65 in the joint for sealing the joint against ingress of water.

As will be noted, the pressure of the water is equal per unit of area at the points 74, 75, and on the top of the piston 69.

70 With a fluid of the same viscosity filling the cylinder, as that of the water, there would be no sealing effect, except as to the chamfered collar and its seat. However, with a substantially heavy oil or grease in the cylinder, under normal atmospheric conditions, the spring urges the

lubricating medium into the crevices and between the shaft and its bushings, this being the condition of non-submergence.

When the dredge is submerged, the pressure on the piston is increased just as the pressure at 5 74 and 75 is increased, and the excess pressure of the spring is still maintained, operating under the same conditions as previously, to lubricate the bearings. The pressure exerted on the grease through the piston by the water is equalized by the pressure of the water on the grease at the end of the bearing. The shaft is forced back by the pressure on the end of the shaft against either a straight or chamfered collar and forms a seal to back up the pressure of the grease. 10 The break-down pressure of a thin film of grease is very high.

Furthermore, the distance from 67 to the chamber is greater than the distance from the chamber to 59, thus the resistance of the grease 20 against urge by the piston is less at 76 than it is at 77, so that with proper proportioning, the seal will operate without the collar 64. Therefore the pressure is equalized between 78 and 74 15 in respect to the piston and increased at 78 25 in respect to the spring 70.

The constant excess pressure of the spring overcomes any breaking down of the grease adjacent the outer end of the bearing and constantly urges a slight amount of grease from the point 30 74, irrespective of the hydrostatic pressure.

Obviously, the cylinder may be inverted and carried to a greater depth to secure the added urge for the grease, however, the matter is simplified by the use of the spring. A rubber 35 washer or other packing means such as a gland may be used additionally as indicated at 79 if desired, and in some cases may be desirable, especially to prevent escape of grease into the 40 enclosure.

The motor housing or enclosure 40 is made of suitable shape, material and strength to withstand the highest hydrostatic pressures to which it is to be subjected. The sealing means is entirely automatic in its action, since any increase 45 in hydrostatic pressure urging ingress of water through the crevices or about the shafts is immediately counteracted by the same increase in pressure on the lubricating medium, the spring providing the excess urge of the grease necessary 50 to maintain a supply at the end of the bearing.

Furthermore, any increase in hydrostatic pressure on the end of the shaft at 65 increases the thrust on the collar 64, while the pressure on the 55 grease in the cylinder provides the necessary lubrication to the collar.

The flexible raising and lowering means for the dredge consists of a chain or cable 80 which is suitably anchored at the transverse center of 60 gravity of the unit, whereby, when the unit, or dredge, is lowered, it will strike the bottom of the sea in a vertical position.

As the dredge strikes the bottom, the spud 65 45 first enters the sub-surface material, and when the dredge comes to rest, or slightly before, the motor 44 is connected in circuit by means of a suitable switch at the surface, (not shown), current being supplied through suitably sheathed 70 conductors 81, the motor driving the spud 45 and also the cutter head with its cutters 30, boring into the sub-sea material, the entire dredge settling into the sludge, the sludge passing into the receiver, the dredge being maintained against 75

rotation by the spud 45, which may be made of any length necessary.

When a settlement of the dredge about equal to the length of the receiver is gauged, the dredge 5 is raised to the surface by means of suitable winches or hoists (not shown), the valve system retaining the sludge in the receiver.

When the dredge is ready to be dumped, the motor 49 is cut in circuit through a suitable reversing switch (not shown), which through the cable 56 permits the dump body 19 with all of its associated parts to swing about the pivot 28. The teeth on the pinion 34 and gear 25 are 10 suitably end chamfered to cause unobstructed registration when the dump body is again closed by the motor 49.

Where a watery pulp is encountered, the holes 15 12 must be dispensed with, and a suitably valved opening used, such as that shown in Fig. 8, in which a flap valve 93 having a resilient facing 10 94 is retained partly open under atmospheric pressure by a spring 95, and fully open by the rush of water as the dredge is lowered, and retained tightly closed by the urgency of the water 20 when the dredge is raised, sealing the receiver.

Three modifications of the system of packing are shown, all of which are effective.

In Fig. 6, the shaft 82 has an integral collar 30 83 and a slip collar 84 urged apart by a resilient washer 85 which tightly grips the shaft, and which may be circumferentially grooved as indicated at 86 and provided with an encompassing spring 87, the collars bearing in seats as shown. By this means, the water of ingress is forced to 35 follow a circuitous route about the collars and through the grease in the chamber. Felt washers are additionally provided.

Both of these collars may be mounted free on the shaft, if desired. The thrust of the shaft 40 is taken up by the ball bearings 87', and the resilient washer tightly grips the shaft and urges the collars to their seats, forming a perfect seal in conjunction with the grease under pressure.

In Fig. 7, the bevel collar 64 on shaft 63 is relieved of the thrust exerted by the water on the end of the shaft, this thrust being absorbed by a fixed thrust collar 89, the bushing 62 being adjusted to contact collar 64 to any desired degree of pressure by means of the gland 90 which is locked in adjusted position by the lock nut 91. Thus the bearing of the bevel collar 64 50 may be adjusted to the most suitable contact pressure.

In Fig. 9, another modification is shown in which opposed bevel collars 96 and 97 are provided, the collar 96 absorbing the thrust, and collar 97 forming a seal in cooperation with the bearing 98, which is adjustable relative to the collar by means of the gland 99, the grease in the 55 chamber and bearings under both spring and hydrostatic pressure effectively sealing the shaft against ingress of water.

Having described an operative device for, and method of deep-sea dredging, it will be understood that variations in construction and arrangement of parts, or in the method, which are consistent with the appended claims may be resorted to without detracting from the spirit or scope of the invention or sacrificing any of the 60 advantages thereof.

I claim:

1. A submarine dredge, in combination, sludge receiving means and sealing means therefor including sludge retaining means and releasing 65 means for the retaining means, boring means

and driving means including an enclosure therefor, and means actuated by the external water pressure for maintaining said driving means against ingress of water thereto, anchoring means for maintaining said receiving means against axial rotation relative to a sub-surface, and flexible raising and lowering means for said dredge. 5

2. A submarine dredge, in combination, a cylindrical receiver, a motor housing mounted at the top of said receiver and a motor within the 10 housing and having a drive shaft projecting through the wall of the housing and a bearing for the shaft, an annular chamber formed intermediate the length of the bearing about the shaft and a lubricating medium within the chamber, 15 means for transmitting the pressure of the water to the lubricating medium to counteract the pressure of the water urging ingress between the bearing and the shaft to prevent ingress thereof to the motor and to lubricate the shaft, a valve 20 system at the lower end of said receiver for admitting sludge into the receiver and for retaining the admitted sludge, a rotary cutter below the valve system driven by said shaft, means for dumping the sludge from the receiver, a spud 25 actuated in advance of the cutter for anchoring the receiver against rotation, and flexible raising and lowering means for said dredge.

3. A submarine dredge, in combination, a sludge receiver and anchoring means therefor, boring 30 means rotatable independently of the receiver and following the anchoring means, driving means for the boring means and for the anchoring means, an enclosure for the driving means and a driving shaft projecting through the 35 wall of the enclosure, means actuated by the external pressure of the water for lubricating the shaft against the external pressure of the water and preventing ingress thereof, means for admitting sludge to the receiver and for retaining 40 the sludge therein, means for dumping the sludge at will, and means for raising and lowering the dredge.

4. In combination, a receiver and hydrodynamically actuated sealing means and gravity actuated entrapment means therefor, a housing, an electric motor in said housing and having a drive shaft projecting through the wall of the housing, means associated with the shaft and actuated 45 by the external pressure of water for counteracting the pressure of the water against ingress about the shaft, a cutter head on said receiver for urging said receiver into the sludge, means for driving said cutter head by said shaft, and means associated with said receiver and cooperating with the sludge for maintaining said receiver against rotation as the cutter head is rotated. 55

5. In combination, a receiver including hydrodynamically actuated sealing means and resiliently actuated sludge entrapment means, a housing, an electric motor in said housing and having a drive shaft projecting through the wall of the housing, means associated with the shaft and 60 the housing and actuated by the external pressure of the water for counteracting the pressure of the water seeking ingress about the shaft, a cutter head on said receiver for urging said receiver into the sludge, means for driving said cutter head by said shaft, means for maintaining said receiver against axial rotation as the cutter head is rotated, said means being associated with the receiver and cooperating with the said sludge entrapment means, means admitting the sludge 65 70 75

into the receiver and retaining the admitted sludge, and means for dumping the sludge at will.

6. A submarine dredge, in combination, a receiver including hydrodynamically actuated sealing means and resiliently actuated sludge entrapment means and a cutter head for the receiver, a motor enclosure integral with the receiver and a motor within the enclosure, a drive shaft projecting through the wall of the enclosure for driving the cutter head, means actuated by the existent external pressure of the water for counteracting the pressure of the water about the shaft to prevent ingress thereof, said entrapment means retaining sludge in said receiver and means for dumping the sludge from the receiver at will, flexible raising and lowering means for said dredge, and anchoring means associated with said receiver and cooperating with sub-surface sludge for maintaining said receiver against axial rotation when the cutter head is driven.

7. A submarine dredge comprising a cylindrical receiver, a cutter head rotatable independently of the receiver and mounted at the lower end thereof, a spud associated with said receiver and operating in advance of the cutter head for maintaining said receiver against axial rotation when the cutter head is operated, means for admitting sludge into the receiver as the receiver is advanced into a bed of sludge and for retaining said sludge means actuated by hydrodynamic pressure when the receiver is raised from the bed sealing the receiver against circulation or passage of water or sludge, and means for driving said cutter head and said spud.

35 8. A submarine dredge comprising a cylindrical receiver, a cutter head rotatable independently of the receiver and mounted at the lower end thereof, a spud associated with said receiver and operating in advance of the cutter head for main-
40 taining said receiver against axial rotation when the cutter head is operated, means for admitting sludge into said receiver as the receiver is advanced into a bed of sludge and for retaining said sludge when the receiver is raised from the bed, means for driving said cutter head and said spud, means for dumping said sludge, and flexible raising and lowering means for the dredge.

9. In combination with a gravity operated submarine dredge having a receiver provided with sludge admitting and retaining means and dumping means; a spud associated with the receiver and operated by said driving means in advance of the cutter head for maintaining the receiver against rotation on its own axis to permit driving of the cutter head independently of the receiver, and flexible raising and lowering means for the dredge.

50

55

60 10. A submarine dredge, in combination, a sweep coextensive with the receiving means and driving means therefor, boring means having a sweep coextensive with the receiving means and driving means therefor, and means actuated by the external water pressure maintaining said driving means against ingress of water thereto, power driven rotary, eccentrically located anchoring means maintaining said receiving means against rotation relative to a sub-surface, and flexible raising and lowering means for said dredge.

65

70 11. A submarine dredge, in combination, sludge receiving means, sludge retaining means and releasing means therefor, boring means and driving means therefor, means actuated by the external water pressure maintaining said driving means against ingress of water thereto, anchoring means

maintaining said receiving means against rotation relative to a sub-surface, flexible raising and lowering means for said dredge, and valve means for said receiver maintained in normally open position under static pressure and maintained in closed position under the influence of hydrodynamic pressure as the dredge is raised through the water to prevent escape of sludge from the receiver.

12. A submarine dredge, in combination, sludge 10
receiving means, sludge retaining means diamet-
rally coextensive with the receiving means and
releasing means therefor, boring means having a
sweep coextensive with the receiving means and
driving means therefor, means actuated by the 15
external water pressure maintaining said driving
means against ingress of water thereto, power
driven rotary, eccentrically located anchoring
means maintaining said receiving means against
rotation relative to a sub-surface, flexible raising 20
and lowering means for said dredge, and valve
means for said receiver maintained in normally
open position under static pressure to permit re-
ception of sludge and escape of water from the
receiver and maintained in closed position under
the influence of hydrodynamic pressure as the 25
dredge is raised through the water to prevent
escape of sludge from the receiver.

13. A submarine dredge, in combination, a
sludge receiver and anchoring means, therefor,
boring means rotatable independently of the re-
ceiver and following the anchoring means, driving
means for the boring means and for the anchoring
means, an enclosure for the driving means and a
driving shaft projecting through the wall of the
enclosure, means actuated by the external pres-
sure of the water for lubricating the shaft against
the external pressure of the water and preventing
ingress thereof, means for admitting sludge to the
receiver and for retaining the sludge therein,
means for dumping the sludge at will, means for
raising and lowering the dredge, and valve means
for said receiver maintained in normal open posi-
tion except under the influence of hydrodynamic
pressure created by raising of the dredge through
the water and which closes and maintains the
valve in closed position. 30 35 40 45

14. A submarine dredge, in combination, a cylindrical receiver, a motor housing mounted at the top of the receiver and a motor within the housing and having a drive shaft projecting through the wall of the housing, means utilizing the external water pressure for counteracting the pressure of the water urging ingress about the shaft to the housing, a valve system at the lower end of the receiver admitting sludge to the receiver and for retaining the admitted sludge, a rotary cutter beneath the valve system and driven by said shaft, means for dumping the sludge from the receiver, an eccentrically located boring spud actuated in advance of the cutter for anchoring the receiver against rotation, flexible raising and lowering means for said dredge, and valve means for said receiver maintained in normal open position except under the influence of hydrodynamic pressure created by raising of the dredge through the water and which closes and maintains the valve in closed position to air-lock the receiver to prevent escape of sludge. 70

15. In combination, a receiver, a housing, an electric motor in said housing and having a drive shaft projecting through the wall of the housing, means associated with the shaft and actuated by

the external water pressure counteracting the pressure of the water urging ingress about the shaft, a cutter head at the bottom of said receiver for urging said receiver into the sludge, means for driving said cutter head by said shaft, rotatable means associated with the receiver and driven by said shaft and cooperating with the sludge for maintaining said receiver against rotation as the cutter head is rotated, and valve means for said receiver maintained in normal open position except under the influence of hydrodynamic pressure created by raising the dredge through the water and which closes and maintains the valve in closed position to prevent escape of sludge from the receiver.

16. In combination, a receiver, a housing, an electric motor in said housing and having a drive shaft projecting through the wall of the housing, means associated with the shaft and the housing and actuated by the external water pressure for counteracting the pressure of the water seeking ingress about the shaft, a cutter head at the lower end of said receiver urging said receiver into sludge, means for driving said cutter head by said shaft, boring means operating in advance of the cutter head into the sludge maintaining the receiver against rotation as the cutter head is rotated, means for admitting sludge into the receiver and for retaining the admitted sludge, means for dumping the sludge at will, and valve means on said receiver normally open to permit circulation through the receiver and closed and maintained closed through the influence of hydrodynamic pressure created by upward movement of the dredge through the water.

17. A submarine dredge, in combination, a receiver and a cutter head mounted for rotation at the bottom thereof, a motor enclosure integral with the receiver and a motor within the enclosure, a drive shaft projecting through the wall of the enclosure for driving the cutter head, means actuated by the external water pressure for counteracting the pressure of the water about the shaft to prevent ingress thereof, retaining means diametrically extensive with the interior of the receiver for retaining sludge in said receiver and means for dumping the sludge from the receiver at will, flexible raising and lowering means for said dredge, and power driven rotary, eccentrically located anchoring means associated with said receiver and cooperating with sub-surface sludge for maintaining said receiver against rotation when the cutter head is driven, and valve means on said receiver normally retained in open position to permit circulation through the receiver and closed and maintained closed through the influence of hydrodynamic pressure.

18. A submarine dredge comprising a cylindrical receiver, a cutter head diametrically coextensive with and rotatable independently of the receiver and mounted at the lower end thereof, a rotatably driven spud associated with said receiver and operating in advance of the cutter head and eccentrically located for maintaining said receiver against axial rotation when the cutter head is operated, means admitting sludge into said receiver as the receiver is advanced into a bed of sludge and for retaining said sludge when the receiver is raised from the bed, means for driving said cutter head and said spud, and means actuated by the existent external water pressure for bucking water under existent pressure against ingress to the prime mover for the means for driving.

19. A submarine dredge comprising a cylindrical receiver, a prime mover and an enclosure therefor, and a shaft projecting through the wall of the enclosure, a cutter head diametrically coextensive with and rotatable independently of the receiver and mounted at the lower end thereof, a rotatably driven spud associated with said receiver and operating in advance of the cutter head and eccentrically located for maintaining said receiver against axial rotation when the cutter head is operated, means admitting sludge into said receiver as the receiver is advanced into a bed of sludge and for retaining said sludge when the receiver is raised from the bed, means for driving said cutter head and said spud, means actuated by the existent external pressure of the water for bucking water under the existent pressure seeking ingress to the prime mover about the shaft, and valve means on said receiver normally retained in open position to permit circulation through the receiver and closed and maintained closed through the influence of hydrodynamic pressure created in raising the dredge.

20. A submarine dredge comprising a cylindrical receiver, a prime mover and an enclosure therefor, and sealing means for the enclosure actuated by the existent external water pressure, a cutter head diametrically coextensive with and rotatable independently of the receiver and mounted at the bottom thereof, a rotatable spud eccentrically associated with said receiver and operating in advance of the cutter head maintaining said receiver against axial rotation when the cutter head is operated, means for admitting sludge into said receiver as the receiver is advanced into a bed of sludge and for retaining said sludge when the receiver is raised from the bed, means for driving said cutter head and said spud by said prime mover, means for dumping the sludge, and flexible raising and lowering means for the dredge.

21. A submarine dredge comprising a cylindrical receiver, an existent water pressure sealed enclosure and a prime mover therein, a cutter head diametrically coextensive with and rotatable independently of and mounted at the bottom of the receiver, a rotatable spud eccentrically associated with and operating in advance of the receiver for maintaining said receiver against axial rotation during operation of the cutter head, means for admitting and retaining sludge in said receiver, means for dumping the sludge, means for driving said cutter head and said spud by said prime mover, flexible raising and lowering means for the dredge, and valve means normally retained in open position to permit circulation through the receiver, and closed and maintained closed under the influence of hydrodynamic pressure created by lifting movement of the dredge for preventing escape of sludge during raising of the dredge.

22. In combination with a gravity operated submarine dredge having a receiver provided with sludge admitting and retaining means and dumping means; a rotatably driven spud eccentrically associated with the receiver operating in advance of the receiver for maintaining the receiver against rotation on its own axis.

23. In combination with a gravity operated submarine dredge having a receiver provided with sludge admitting and retaining means and dumping means; valve means associated with said receiver normally retained in open position to per-

mit circulation through the receiver during operation of the dredge, and closed and maintained closed under the influence of hydrodynamic pressure when the dredge is raised through the water to prevent escape of sludge from the receiver.

5 24. In combination with a deep-sea dredge having a receiver consisting of a container section and a dumping section hinged together; a rotatably driven cutter head mounted at the bottom of the dumping section and having a sweep

diametrically coextensive with the bottom of the dumping section, and a diametrically coextensive valve system within the dumping section above the cutter head permitting passage of material therethrough as the receiver settles into the bore formed by the cutter head and entrapping the material and means actuated by hydrodynamic pressure sealing the receiver during raising of the dredge.
